SHEET-METAL CULVERT

Application filed April 2, 1929. Serial No. 351,953.

My invention relates to improvements in sheet metal culverts, and the object of the invention is to devise a culvert of this type which will have maximum durability, which 5 will provide free, unobstructed water flow, and may be easily freed from accumulated matter or ice or snow, which will provide complete drainage so that there will be no pocketing of moisture in the culvert bottom 10 tending to corrode the same, and in which any sediment lying at the bottom of the culvert will not be held in corrugations, and it consists essentially of the arrangement and construction of parts as hereinafter more 15 particularly explained.

Fig. 1 is a perspective view of a portion of a sheet metal culvert constructed in accordance with my invention.

Fig. 2 is a longitudinal sectional view 20 through Fig. 1, taken on line 2—2, Fig. 3.

Fig. 3 is a transverse sectional view through the culvert.

1 and 2 are two culvert sections. Each 25 section is formed with an upper corrugated peripheral portion, the corrugations extending transversely of the section. The lower peripheral portion of the culvert is depressed as indicated at 4 so as to form a trough-like 30 depression having a smooth surface free from corrugations so that any water or moisture accumulating at the bottom of the culvert will have a free flow over such surface, and thereby provide for complete drainage.

The longitudinal edges of the portion 4 are 35 formed into shoulders 4^x which serve to reinforce the culvert section longitudinally. The sections of the culvert fit one into the other in the usual manner and are connected together 40 by tie-plates 5 riveted as indicated at 6, to the overlapping ends of the culvert sections.

Each tie-plate 5 is provided with a central 45 corrugation 7, forming an exterior rib around the lower portion of the culvert, serving to engage the ground surface in which the culvert is embedded and thereby prevent longitudinal movement. Although I show the tie-plate 5 located at the joint between the culvert sections, it will of course be understood 50 that they might be placed at suitably spaced

apart points along each section of the culvert as found desirable.

By the construction above set forth it will be readily understood that I have provided a sheet metal culvert which will be rendered 55 strong and durable by reason of its corrugated upper portion, and at the same time will provide for the free flow and drainage of water along the lower surface of the culvert, eliminating the formation of pockets in 60 which matter may accumulate or ice and snow congregate. When the lower portion of the culvert is corrugated, the ice and snow particularly engage in such corrugations so that it is impossible to clear the culvert until such 65 ice and snow has slowly melted.

Also by forming the lower portion of the culvert with corrugations pockets are formed in which water is retained for a considerable length of time which thereby tends to corrode 70 the interior surface of the culvert, reducing the life thereof.

What I claim as my invention is:—

A pair of corrugated sheet metal pipes inserted at their ends one within the other so 75 that the end corrugations interengage, and a semi-cylindrical tie-plate adapted to fit the engaging corrugations and to be riveted at one side to one pipe end at the one side of the engaging corrugations and at the other side 80 to the other pipe end at the other side of the engaging corrugations.

WILLIAM ELWOOD BABE.
